US00D505078S

(12) **United States Design Patent** (10) Patent No.: **US D505,078 S**
Fischer et al. (45) Date of Patent: **** May 17, 2005**

(54) **SUBSTANCE APPLICATOR**

(75) Inventors: **Jeffrey Fischer**, Warminster, PA (US);
Mary Ann Alexander, Holland, PA (US)

(73) Assignee: **Clarence J. Venne, L.L.C.**, Levittown, PA (US)

(**) Term: **14 Years**

(21) Appl. No.: **29/187,887**

(22) Filed: **Aug. 8, 2003**

(51) LOC (7) Cl. **09-01**

(52) U.S. Cl. **D9/538; D9/539; D9/557**
